UNITED STATES PATENT OFFICE.

BERT L. SINCLAIR, OF KANSAS CITY, KANSAS, ASSIGNOR OF ONE-HALF TO JOHN W. JONES, OF KANSAS CITY, KANSAS.

JACKET AND APRON.

1,134,643.

Specification of Letters Patent.

Patented Apr. 6, 1915.

Application filed October 14, 1913, Serial No. 795,123. Renewed January 19, 1915. Serial No. 3,172.

To all whom it may concern:

Be it known that I, BERT L. SINCLAIR, a citizen of the United States, residing at Kansas City, in the county of Wyandotte, State of Kansas, have invented certain new and useful Improvements in Jackets and Aprons, and I do hereby declare the following to be a full, clear, and exact description of the invention, such as will enable others skilled in the art to which it appertains, to make and use the same.

This invention relates to improvements in apparel and particularly to a coat and apron to be worn by a cook or the like.

15 The principal object of the invention is to provide a coat to be worn by cooks, butchers, grocers or the like which will be both comfortable and neat.

20 Other objects and advantages will be apparent from the following description, when taken in connection with the accompanying drawings.

25 In the drawings: Figure 1 is a perspective view of my invention. Fig. 2 is a view of the coat open.

With the coats and aprons generally used by cooks, butchers, grocers and the like, the apron is tied over the coat. The tail of the coat in time rides up and gets into a thick bunch which makes the same hot and uncomfortable to the wearer. To overcome this defect, I provide the coat 10 with the side slits 11 which extend to the waist line or a slight distance thereabove. On the 30 front portion of the coat, and in a line coincident with the waist line are secured a plurality of fasteners, such as the buttons

12 with which are engaged the series of button holes 13 formed in the waist band 14 of the apron 15. The apron is thus smoothly 40 and neatly held over the front of the coat. The strings 16 of the apron are tied around the waist of the wearer under the rear or tail portion 17 of the coat. This leaves the tail portion hanging freely so that the coat 45 will be more comfortable by reason of the absence of this thickness under the apron strings, and also permits air to get under the tail of the coat, so that the wearer does not suffer any great inconvenience from the 50 heat.

The sleeves 18 are slit as indicated at 19 and provided with buttons and button holes so that the wrist bands can be drawn snugly around the wrists and hold the sleeve 55 out of the way of the wearer while at work, thus producing a garment which is both comfortable and sanitary.

What is claimed is:

An article of apparel comprising a coat 60 which is slit at the side up to the waist line, the front portion of the coat having a series of fasteners arranged along the line of the waist line, and an apron having fasteners for engaging the coat fasteners, the said 65 apron being arranged to be secured at the back of the waist of the wearer under the tail of the coat.

In testimony whereof, I affix my signature, in the presence of two witnesses.

BERT L. SINCLAIR.

Witnesses:

WILLIS ALLEN,
F. D. GLEED.
